UNITED STATES PATENT OFFICE.

JOHN F. O'CONNOR, OF CHICAGO, ILLINOIS, ASSIGNOR TO WILLIAM H. MINER, OF CHAZY, NEW YORK.

HOISTING APPARATUS.

1,226,578.

Specification of Letters Patent. Patented May 15, 1917.

Application filed August 17, 1914. Serial No. 857,105.

To all whom it may concern:

Be it known that I, JOHN F. O'CONNOR, a citizen of the United States, residing at Chicago, in the county of Cook and State of Illinois, have invented a certain new and useful Improvement in Hoisting Apparatus, of which the following is a full, clear, concise, and exact description, reference being had to the accompanying drawings, forming 10 a part of this specification.

This invention relates to improvements in hoisting apparatus.

An object of the invention is to provide a hoisting apparatus of few parts simply arranged and so constructed that it is automatically self-locking in position.

Another object of the invention is to provide a hoisting apparatus employing differential gearing in which the winding drum and pinions are mounted on the same shaft to thereby produce a compact structure.

Other objects of the invention will appear from the description hereinafter given.

In the drawings forming a part of this specification, Figure 1 is a side elevation of one form of hoisting apparatus embodying my improvements and showing the position of the same as it would be attached to a vertical post or side of a building; Fig. 2 is a 25 vertical diametrical sectional view taken substantially on line 2—2 of Fig. 1; and Fig. 3 is a transverse sectional view taken substantially on line 3—3 of Fig. 2.

In said drawing, 10 denotes a bracket suitable for supporting the hoisting apparatus proper, said bracket 10 comprising a rear vertical wall 11 adapted to be secured to a post or pillar 12 by means of bolts or other suitable fastening devices 13. Said bracket 40 10 also has two spaced forwardly extended arms 14—14, each of which is provided with a bearing 15, the latter having mounted therein a square operating shaft 16, the latter being provided with suitable bushings 17 fitting the shaft 16 and also the bearings 15. The shaft 16 has secured thereto, outside of the bearings 15, collars 18—18, the latter being held in position by set-screws 19—19. The shaft 16 may be rotated by any suitable 50 means, such as a crank arm indicated in dotted lines at 20 in Fig. 2. At its central portion the shaft 16 is fitted with another bushing 21 which serves as a bearing for the hub 22 formed integrally with the winding 55 drum 23, the latter having a central spider

24 connecting it with the hub 22. The drum 23 is also provided with peripheral flanges 25, to one of which is attached a screw-eye 26 by which the end of the cable or rope being wound upon the drum can be attached thereto. Each end of the drum 23 is provided with a large, internal annular gear 27,—see Figs. 1 and 3. Mounted within the annular gears 27 are pinions 28, the pinions 28 being of slightly less diameter than the pitch diameter of the gears 27 and having a less number of teeth. In actual practice, the pinions 28 will or may be provided with forty-eight teeth, whereas the gears 27 will have 51 teeth. Each pinion 28 is mounted 60 on an eccentric 29 fixed to the shaft 16, the eccentrics 29 being disposed at substantially 180 degrees apart so that, as shown from Figs. 1 and 3, the pinion at one end of the drum will be in engagement with its coöperating gear 27 at the bottom, and the other pinion 28 will be in engagement with its corresponding gear 27 at the top, and this 70 180-degree relation will be maintained at all times as the shaft 16 is rotated and the points of engagement between the pinions and the gears is shifted. To prevent the pinions 28—28 from rotating, pins 30 are provided formed on the inner ends of bolts 31 which are secured into corresponding 75 threaded sockets in the arms 14—14, the pins 30 at one end of the drum being arranged in vertical alinement, as shown in Fig. 3, and the pins at the opposite end of the drum being arranged in horizontal alinement, as 80 shown in Fig. 1. The pins 30 engage in holes or recesses 32 formed in the pinions 28, the holes or recesses 32 being sufficiently 85 large to permit the pinions to accommodate themselves during their movements caused by the rotation of the cams 29—29.

From the preceding description, it is believed that the operation will be clear, it being evident that as the crank arm 20 is rotated, the points of engagement between the pinions and gears will travel in a circle around the gears, and inasmuch as there are fewer teeth on the pinions than on the gears, the drum will be advanced or moved 100 backwardly an amount equal to the difference between the number of teeth on the gears and pinions. For instance, when the pinions have forty-eight teeth and the gears fifty-one teeth, the amount of movement of the drum will equal three teeth for each 105 110

revolution of the shaft 16, so that seventeen rotations of the shaft 16 will rotate the winding drum one complete revolution. As will be obvious, the ratio of teeth in the differential gearing may be varied as desired, depending upon the work to be performed by the hoisting apparatus. It will furthermore be observed that the device is self-locked in whatever position the parts 10 may be left in, thus doing away with the necessity for dogs, latches or other complicated latching devices, which are not only expensive, but require a certain amount of extra care and precaution in operating the 15 hoist.

Although I have herein shown and described what I now consider the preferred embodiment of my improvement, yet it will be understood by those skilled in the art 20 that various changes and modifications may be made in the details and arrangements without departing from the spirit of the invention, and all such changes and modifications are contemplated as come within the 25 scope of the claim appended hereto.

I claim:—

In mechanism of the character described, the combination with a supporting member having a pair of spaced, integral, outstanding arms, each arm having a bearing therein, of a winding drum mounted between said arms, said drum having internal gears at each end thereof and a centrally located bearing, pinions of lesser pitch diameter than said gears and coöperable therewith, 30 said pinions being bodily movable but non-rotatable and relatively angularly displaced 180 degrees, eccentrics on which said pinions are mounted, an operating shaft removably extended through said bearings in said arms 35 through said eccentrics, and through said bearing on the drum, said eccentrics being rotatable with said shaft, and pins carried by said arms and extending into slots in the pinions for preventing rotation of the latter. 40 45

JOHN F. O'CONNOR.
